UNITED STATES PATENT OFFICE.

ANDREW J. GILBERT AND GEORGE WENDLING, OF NORWALK, CONN.

PORTRABLE OVEN.

SPECIFICATION forming part of Letters Patent No. 317,938, dated May 12, 1885.

Application filed January 30, 1884. (No model.)

To all whom it may concern:

Be it known that we, ANDREW J. GILBERT and GEORGE WENDLING, both citizens of the United States, and residents of Norwalk, in 5 the county of Fairfield and State of Connecticut, have invented new and useful Improvements in Portable Ovens, of which the following is a specification.

The object of our invention is to provide a simple, practicable, and efficient portable brick oven having all the advantages of the common brick ovens, and being at the same time so constructed that it may be moved about from place to place without injury to it and 15 without taking it apart.

In carrying out our invention we make a metallic base having provision for a fire-grate and ash-pan, and being adapted to support a brick floor with an insulating layer of sand 20 below the brick to retain the heat, and we construct a superstructure of arched beams supporting a brick covering and sand-jacket with a metallic cover to retain the sand, and with a door-casing and door at one end to 25 facilitate ingress, also with a smoke-pipe connection for the escape of the smoke, and having a damper to close the same when the heat is to be retained for baking, all as hereinafter 30 fully described, reference being made to the accompanying drawings, in which—

Figure 1 is a longitudinal sectional elevation of our improved portable oven. Fig. 2 is a transverse section of the same with the door shown in front elevation. Fig. 3 is a 35 sectional detail of some of the parts on a larger scale.

We make a base-plate, *a*, for the support of the floor or hearth, and also the arch for enclosing the floor, with a vertical marginal 40 flange, *b*, to rest on a brick or other temporary or permanent support, *c*, also with a depressed section, *d*, embracing the larger interior or middle portion of the plate, and forming a pan having an offset, *e*, in the side walls 45 to support the bricks *f* of the hearth or floor of the oven flush with the surface of the plate, said offset being level with the lower edge of the flange *b*, and serving, if desired, for an inner bearing to rest on the brick wall or other 50 support *c*. From the offset *e*, for the support of the brick floor, the depression *d* extends a suitable distance for containing an insulating

layer, *g*, of sand of suitable depth for preventing the escape of the heat. Said plate *a* is also constructed with supporting-edges *i* for a fire-grate, *h*, extending the length of the depressed portion *d*, near one side of the same, and with partitions *j* extending from said ledges *i* down to the bottom of the plate, which is made with an opening under the grate through which the 60 ashes may fall into a pan, *k*, attached to the under side of said plate, or it may be formed together with the bottom plate, if desired. 55

Along the middle of the depression *d*, and parallel with the grate-supporting ledges *i*, we 65 arrange a support, *l*, for the meeting ends of the hearth-bricks *f*, over which we arrange a cross-bar, *m*, extending from side to side of the depression *d*, and resting on plate *a* at its ends, with one or more bolts, *n*, extended down 70 through support *l*, and the plate to hold the bar in place for a binder to the floor-bricks, said bricks being rabbeted along the upper corners to allow the bar to set in flush with the upper surface of the bricks. 75

Where the bolt or bolts *n* extend through the bottom of the plate we form a recess or 75 recesses, *o*, for the ends of the bolts and nuts, to prevent them from projecting below the bottom of the plate, for enabling the plate to 80 rest flat on any support in case it may be desired.

The flange *b* and the ledge *e* of the plate *a* elevate said plate on the supports *c*, and form 85 cavities under the marginal portions of said plate to be filled with sand *g*, to economize the heat.

Over the floor or hearth *f* we arrange a brick arch, *q*, consisting of a single layer of suitably-curved bricks supported intermediately on 90 the metal arched *L*-beams *t*, and at the rear on the bevel-flanged arched beam *u* with a vertical front end wall, *v*, and a curved back wall, *w*. The back end wall leans against the bevel-flanged side of the arch-beam *u* for the 95 bearing of its upper end, and the front end wall, *v*, has an opening through it for the doorway, and over said opening rests on the metallic doorway-arch *x*, which is as much wider than the thickness of the wall *v* as is required 100 for the thickness of the insulating sand-jacket *y*, with which we cover the brick top of the oven, and said doorway has a flange, *z*, at the outer edge which connects with the inside of

the front end plate, a' , of the exterior metal jacket or case for retaining the sand, which case consists, besides said front end plate, of the arch b' , made of several curved plates placed edge to edge and matched by an offset flange, c' , of one plate overlapping the plain edge of the next, and the curved back end plate, d' , which matches onto the rear ends of plates b' by the flange e' , offset on the inner sides of said plates b' , forming a ledge, against which the arched end of plate d' bears, while the lower end, together with the lower edges of the lower arch plates, b' , and the lower end of the front plate, a' , rest on plate a inside of a vertical retaining-flange, p , on the upper surface of said plate a .

The plates b' also have an offset, e^2 , at the front end, forming a rabbet, in which a flange, f^2 , of the end plate, a' , fits for the connection of the arch and the front end, a' . The door f' closes against the front side of the end plate, a' , and a ledge, g' , of the bottom plate, a , a little below the surface of the hearth, to allow the coals to be readily raked out after heating the furnace sufficiently for baking, said door opening to about the center of the width of the grate h' to facilitate the firing through said door and avoiding the use of a special door to the fire-grate.

At the rear end of the oven and diagonally across from the front end of the fire-grate we notch the edge of one of the arch-bricks, q , and the ends of some of the end bricks, w , suitably to form a hole for the escape of the smoke, and fit in said hole a short section of pipe, i' , having suitable beveled ends to correspond with the interior and exterior shapes of the oven-top; also, flanges j' to rest on lugs k' of the arch-beam u to hold said pipe in position on the outer jacket, and coincident with the pipe i' we attach another pipe-section, l' , having a base, m' , containing a sliding damper, n' , to close the passage and prevent the escape of the heat when the fire is removed and the oven is employed for baking.

We also propose to line the door with brick o' to prevent waste of heat through it.

Fig. 3 shows the pipes i' and l' , also damper n' , on a larger scale, and the manner in which pipe i' is connected to the beam u .

50

What we claim, and desire to secure by Letters Patent, is—

1. The improved portable oven, consisting of the bottom plate, a , having brick hearth f , fire-grate h' , and sand-filling g , in combination with arch-beams $t u$, brick cover q, v , and w , sand-jacket y , and the metallic sand-retaining jacket a', b' , and d' , constructed and arranged substantially as described.

55

2. The bottom plate, a , constructed with flange b , depressed section d , grate-supports i , and partitions j , and having ledges e and brick-support l , in combination with a superstructure consisting of arch-beams, brick cover, sand-jacket, and a metallic sand-retaining jacket, substantially as described.

60

3. In a brick top for portable ovens, the combination of the arch-beams $t u$, arch-backs q , and vertical front end wall, v , said front wall having a doorway and being supported on the frame x , and said wall w being supported at the junction with the arch by the bevel flange of beam u , substantially as described.

65

4. The combination, with the oven-top, consisting of the arch-beams, fire-brick, sand-jacket, and metallic retaining-jacket, of the pipe i' , resting on the arch-beam u and extending through the fire-brick and sand-jacket to the metallic retaining-jacket, and also of the pipe l' , having the slide-damper n' in its base m' , and being attached to the exterior of the metallic jacket coincident with the pipe i' , substantially as described.

70

In witness whereof we have hereunto signed our names in the presence of two subscribing witnesses.
